UNITED STATES PATENT OFFICE.

WILLIAM D. HAMILTON, OF ALLEGHENY, PENNSYLVANIA.

DESIGN FOR A NAME-PLATE.

SPECIFICATION forming part of Design No. 35,939, dated June 10, 1902.

Application filed April 23, 1902. Serial No. 104,401. Term of patent 7 years.

To all whom it may concern:

Be it known that I, WILLIAM D. HAMILTON, of Allegheny, in the county of Allegheny and State of Pennsylvania, have invented and produced a new and original Design for Name-Plates, of which the following is a full, clear, and exact description, reference being had to the accompanying drawings, forming part of this specification, in which--

Figure 1 is a face view of a name-plate embodying my design, and Fig. 2 is an edge view of the same.

The essential feature of my design consists in a name-plate having a central metallic plate portion, a surrounding metallic rim portion separated therefrom, with connecting-arms between these parts, and fabric portions in the spaces between the central plate and the separated surrounding rim.

In the drawings, 2 represents the metallic 20 central plate portion connected at the corners by arms 3 to a rim portion 4, which extends around the plate. Between the central plate and the rim are fabric portions 5, which contrast in appearance with the metallic central 25 plate and metallic rim.

I claim—

The design for a name-plate substantially as herein shown and described.

In testimony whereof I have hereunto set 30 my hand.

WM. D. HAMILTON.
